[57] CLAIM

The ornamental design for a felt tipped pen, as shown and described.

DESCRIPTION

FIG. 1 is a top, right front perspective view of a felt-tipped pen showing our new design;

FIG. 2 is a front elevational view, the rear view being a mirror image thereof;

FIG. 3 is a right side elevational view, the left side being a mirror image thereof;

FIG. 4 is a front elevational view with the cap member removed for convenience of illustration, the rear view being a mirror image thereof;

FIG. 5 is a top plan view of FIG. 1; and,

FIG. 6 is a bottom plan view of FIG. 1.

FIG. 1

FIG. 2

FIG. 3

FIG. 4

FIG. 5

FIG. 6
